UNITED STATES PATENT OFFICE.

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE.

TYPEWRITING MACHINE.

Application filed July 27, 1925. Serial No. 46,237.

This invention relates generally to type-writing machines, and is directed particularly to means for gaging and holding cards, or the like, against the printing-line of the platen for typing, especially near the bottom edges thereof.

There is provided adjacent the front of the platen a chute for reception of a card or work-piece inserted bottom edge downward, gages being provided for the side edges of the card, and card-gripping means for firmly holding the card against displacement when brought to the printing-line for typing. The chute preferably includes a pair of adjustable wing-plates or tables carried by a suitable frame detachably mounted on the platen-frame; and a resilient second plate overlies each of the first-named plates to provide a channel or chute for the card. The plates preferably have cup-shaped depressions, the ones in the overlying plates projecting into the ones in the associated wing-plates or tables, thereby slightly indenting the card to effect a gripping action thereagainst and thus hold the same within the chute. Guide-fingers extend downward from the plates to insure holding the lower edge of the card against the platen at the printing-line, and gages at the upper edge of the card determine the line-space positions for the lower portion of the card. The upper edge gages include a pair of laterally-adjustable gage-staffs, each carrying vertically-adjustable riders having a plurality of gage-stops, the upper edge of the card being successively positioned against said gage-stops to progressively line-space the card. Due to the fact that all line-spacing is effected by the gage-stops, the platen remains stationary, and is only turned when thought advisable to bring a new striking surface beneath the type. The device is of extreme simplicity, being preferably stamped and bent to shape from thin gage-sheet material, and is consequently inexpensive to manufacture.

One of the features of the invention is the provision of a card-chute having a card-receiving channel of a width somewhat greater than the thickness of the card, thus permitting uninterrupted passage thereof, and interlocking depressions in the front and rear walls of the channel for indenting the card, thereby holding the same in typing-position within the chute.

Another feature of the invention is the provision of a card-chute including two separate sections carrying gages for the side edges of the card, the sections being adjustable through a wide range whereby to accommodate a large variety of cards of different sizes.

Another feature of the invention is the provision of fingers extending downward from the plates at both the front and the back of the card, the rear finger supporting the card, to a point closely adjacent the surface of the platen, and the front finger pressing the lower portion of the card against the platen at the printing-line.

Another feature of the invention is the provision of upper edge gages for the card adjustable independently of the chute, so that the typist has a choice of disposing said gages behind the chute to thus enable the card to be grasped at the middle of its upper edge for removal and insertion, or disposing said gages inward toward the middle of the card, so as to enable the outer edges thereof to be readily grasped. The card may be fully inserted in the chute, and then all adjustments made while the card is in such position.

A further feature of the invention relates to novel means for attaching the overlying plates to the wing-plates or tables of the card-chute.

Other features and advantages will hereinafter appear.

In the accompanying drawings, Figure 1 is a front elevation of the platen and the platen-frame of a typewriting machine, showing the invention applied thereto.

Figure 2 is a perspective view of one portion of the card-chute, and means for mounting the same on the platen-frame, some of the parts being separated for clearness of illustration.

Figure 3 is a vertical section on the line 3-3 of Figure 1.

Figure 4 is a vertical section on the line 4-4 of Figure 1.

Figure 5 is a sectional detail of means for fastening together parts of the card-chute.

Referring particularly to Figure 1 of the drawings, 10 represents a card or work-piece inserted downward adjacent the front of a platen 11 to bring the bottom portion 12 of the card to the printing-line 13 of the platen, said platen being mounted by means

of the usual platen-axle 14 in the side frames 15 of a platen-carriage designated generally by the numeral 16. For guiding a card down to the printing-line, there is provided 5 means including a pair of wing-shaped plates or tables 17, each having a portion of the side edge thereof bent outward to form guides or gages 18 for the side edges of the card 10. The plates 17 also include side ex- 10 tentions 19, each having its lower edge bent inward at 20 and then upward at 21 to engage around the lower edge 22^a of an inverted L-shaped bar 22 supporting the plates 17. The plates 17 are offset at 17^a to provide 15 a space between the back walls of said plates and the bar 22. The upper portion of each of the extensions 19 is bent over at 24 to overlie a ledge 23 of the bar 22, then downward at 25 and then inward at 26 beneath 20 the ledge 23. Thus each of the plates or tables 17 are slidably mounted upon the bar 22. For adjustably securing the plates 17 in any selected position along the bar 22, whereby to accommodate cards of different 25 widths, there are provided set-screws 27 extending downward through the bent-over portions 24 of the extensions 19, and thence through plates 28 interposed between the ledge 23 and said portions 24. Thus it will 30 be seen when the set-screws 27 are turned down upon the ledge 23, the plates 17 are secured to the bar 22. For holding the card 10 in position upon the plates 17, spring- 35 clips or plates 29 are fastened to the extensions 19, and although any suitable fastening means may be employed, I prefer to utilize means such as best illustrated in Figure 5. It will be noted that each of the spring-clips 29 is offset at 30, thus establishing clearance above its associated plate 17, and providing fastening ears 31. The metal of each of the extensions 19 is drawn out at 32 and perforated at 33 to provide a long 40 thread for a screw 34, and an enlarged perforation 35 in each of the ears 31 fits over the drawn out portion 33. A collar or washer 36 maintains the shoulder 37 of the screw 34 sufficiently above the outer limit of the drawn-out portion 33, to cause the pressure 45 exerted by said screw to be transmitted directly to the ear 31, and thus hold the same in firm frictional engagement with the face of the extension 19. Such fastening means permits the clips or plates 29 to be easily 50 removed for instance when it is desired to slightly bend said clips for either increasing or reducing the clearance thereof relative to the plates 17. The spring-clips 29 have their upper edges curved outward at 55 38 from the plates 17 to provide an easy entrance channel for the lower edge of the card 10. It will be observed that the offsets 30 for spacing the clips 29 from the plates 17 are positioned outward from the vertical 60 plane of the guides 18; thus the side edges 65 of the card 10 do not touch said offsets 30. Each of the plates 17 has a depending tongue 39 which extends downward to a point closely adjacent the surface of the platen 11, and engages the rear face of the card, whereby to aid in supporting the same in position for typing. The tongues 39 are especially advantageous when handling thin or flimsy cards. Each spring-clip 29 has a depending finger 40 overlying a tongue 39, 70 said finger 40 extending to a point adjacent the printing-line, so as to securely hold the bottom edge 12 of the card 10 against the platen, to receive impressions of type 41. For securing the card against movement 75 during the typing operation, there is provided gripping means in the form of depressions 42 in the plates 17 and corresponding complementary depressions 43 in the spring-clips or plates 29, the depressions 42 and 43 being preferably cup-shaped. The depressions 43 extend somewhat within the depressions 42, so that when a card is inserted downward between the plates 17 and the spring-clips 29, said depressions bend or indent the card sufficiently to obtain a grip thereon and thus prevent the card from moving out of position. It is to be understood 80 that the plates 17 and the spring-clips 29 are sufficiently spaced from one another, so as not to interfere with the free movement of the card, and that the only holding action against the card is exerted at the point where it is gripped by the interlocking depressions 42 and 43. Perforations 44 may 85 be provided in each of the depressions 42 and 43 for further aiding in gripping the card. For mounting the bar 22 on the machine, there is provided a pair of end plates or supports 45 extending over the out-turned 90 extensions 46 of the frames 15, the plates 45 having perforations 47 for the reception of thumb-screws 48 which thread into the frames 15. The plates 45 include downwardly-bent tabs or walls 49. Each end of 95 the bar 22 has a pair of horizontal slots 50. Screws 51 pass through said slots 50 into threaded engagement with the walls 49, and it is obvious either one of the pairs of slots 100 may be used in attaching the bar 22 to said walls 49. Thus the bar 22 and its associated parts are readily attachable to two different types of machines by simply interchanging the screws 51 with either one of the slots 50. For line-spacing the card 10, and at the same 105 time supporting the same, there is provided a pair of upstanding gage-staffs 52 mounted in sliding relation upon the bar 22 by means of clips 53 of a character similar to those 110 used for attachment of the plates 17. The clips include an upper portion 54 bent over the ledge 23, then downward at 55 and then inward at 56. The lower portion of each 115 clip is bent at 57 around the lower edge 22^a of the bar 22 in a manner similar to the ex- 120 125 130

tensions 19 already described. A screw-threaded plate 58 associated with each of the clips 53 receives a thumb-screw 59, thus providing means for adjusting the gage-staffs 52 in any desired position along the bar 22, and it will be readily understood that said gage-staffs may be moved to adjusted position behind the tables 17. The staffs 52 carry riders 60; and set-screws 61 adjust the vertical position of the riders on said staffs 52, so as to accommodate different depths of cards. The riders 60 include an upper gage-piece 62 and a lower gage-piece 63, against which the upper edge of the card 10 may be progressively positioned, whereby to line-space the bottom edge 12 of the card. For aiding the fingers 40 in holding the card 10 against the platen, the machine preferably includes a wing-scale 64 having the upper edge 20 thereof directed outward, as indicated at 65, from the platen 11, thus facilitating passage of the bottom edge 12 of said card downward past the upper edge of the wing-scale. Spring-pressed rollers 66 are usually employed for pressing the wing-scale 64 toward the platen. If it is desired to detach the card-holder from the machine, it is only necessary to remove the thumb-screws 48 and then lift the whole device from the machine, as a unit. It will also be understood that the device may be readily fitted to another machine differing somewhat from that illustrated herein, and that the lower slot 30 may be conveniently utilized for such purpose.

Variations may be resorted to within the scope of the invention, and portions of the improvements may be used without others.

Having thus described my invention, I claim:

1. In a typewriting machine, the combination with a platen, of a chute for guiding to the printing-line a work-piece inserted bottom edge downward at the front of the platen, said chute including front and rear walls, said rear wall having a depression therein, the front wall being resilient and having a depression fitting into the depression in the rear wall, the depressions being effective to indent and thereby grip the work-piece, said walls being spaced apart a distance greater than the thickness of the work-piece, so that only the indenting action of the depressions holds said work-piece 55 within the chute.

2. In a typewriting machine, the combination with a platen, of a chute for guiding to the printing-line a work-piece inserted bottom edge downward at the front of the platen, said chute including plates at the front and the rear of the work-piece, the front plates having the upper edges thereof turned outward to provide a lip for easy insertion of the work-piece, said plates, each 60 including complementary depressions be-

neath said lip, for indenting the work-piece, whereby to hold the same within the chute, said chute being slidably adjustable longitudinally of said platen substantially throughout the length of the latter. 70

3. In a typewriting machine, the combination with a platen, of a chute for guiding to the printing-line a work-piece inserted bottom edge downward at the front of the platen, said chute including a work-table 75 adjacent each side of the work-piece, and slidably adjustable substantially throughout the length of the platen, each table having a depression therein, guides for the side edges of the work-piece, and resilient plates 80 overlying the work-tables, said resilient plates having depressions fitting into said first-named depressions, for indenting the work-piece, whereby to hold the same within the chute. 85

4. In a typewriting machine, the combination with a platen, and a platen-frame therefor, including side frames, of a support detachably mounted on each of the side frames, a bar extending along the platen and 90 adjustably attached to said supports, a pair of work-tables slidably adjustable upon said bar, substantially throughout the length of the platen, guides carried by the work-tables for the side edges of a work-piece, resilient 95 clips overlying said tables and including means for gripping the work-piece and means for gaging the top edge of the work-piece, whereby to bring the bottom portion of said work-piece to successive line-space 100 positions at the printing-line of the platen.

5. In a typewriting machine, the combination with a platen, and a platen-frame therefor, including side frames, of a support detachably mounted on each of the side frames, each support including a tab-portion, a bar extending along the platen, means for adjustably securing the opposite ends of said bar to the tab-portions, a pair of work-tables slidably adjustable upon said bar, 110 guides carried by the work-tables for the side edges of a work-piece, resilient clips overlying said tables and including means for gripping the work-piece, and gage-means for the top edge of the work-piece, 115 whereby to progressively line-space the bottom of said work-piece, said tables and gage-means being adjustable independently of one another.

6. In a typewriting machine, the combination with a platen, and a platen-frame including side frames, of a support detachably mounted on each of the side frames, each support including a tab-portion, a bar extending along the platen adjacent the top 120 thereof, the opposite ends of said bar being faced against the tab-portions and including a series of horizontal slots arranged in tiers, a fastener passing through a selected slot 125 of each series and thence into threaded re- 130

lation with the adjacent tab-portion, paper-tables slidingly adjustable along said bar and including side gages for the side edges of a work-piece inserted bottom edge downward at the front of the platen, extensions carried by said tables outward from the side edges of the work-piece, adjusting screws carried by said extensions, whereby the tables may be adjusted while the work-piece is within the machine, and means carried by said tables to grip the work-piece.

7. In a typewriting machine, the combination with a platen, of an adjustable chute for guiding and holding to the printing-line a work-piece inserted bottom edge downward at the front of the platen, said chute being adjustable as to width longitudinally of the platen while the work-piece is in typing-position within the chute.

8. In a typewriting machine, the combination with a platen, of an adjustable chute for guiding and holding to the printing-line a work-piece inserted bottom edge downward at the front of the platen, and gage-means, including a plurality of stops, adjacent the top edge of the work-piece against which said top edge may be successively positioned to line-space the work-piece, said chute and gage-means both adjustable while said work-piece is in typing-position within the chute.

9. In a typewriting machine, the combination with a platen, of an adjustable chute for guiding and holding to the printing-line a work-piece inserted bottom edge downward at the front of the platen, the chute being adjustable while the work-piece is in typing position within said chute, and depressions formed in the walls of said chute, whereby to engage said work-piece and thereby hold the same against displacement during typing.

10. In a typewriting machine, the combination with a platen, of a bar attached to the machine adjacent the top of the platen, slides adjustable on said bar substantially throughout the length of said platen, said slides carrying paper-tables including side-edge gages for a work-piece inserted bottom edge downward at the front of the platen, work-piece-supporting tongues extending downward from said tables, and resilient clips carried by said tables including fingers overlying said tongues, said fingers extending downward to points adjacent the printing-line of the platen, whereby to hold said work-piece thereagainst, said clips including depressions directed inward toward said tables, the latter having complementary depressions into which said first-named depressions project, whereby to indent the work-piece and thereby hold the same to said tables.

11. In a typewriting machine, the combination with a platen, of a work-chute in-

cluding a pair of adjustable work-tables, for guiding to the printing-line a work-piece inserted bottom edge downward at the front of the platen, and means for gaging the top edge of the work-piece, whereby to control the line-space positions of the lower portion of said work-piece, said gage-means being movable to position behind said tables.

12. In a typewriting machine, the combination with a platen and a platen-frame therefor, of a bar detachably mounted on the platen-frame and extending along the platen, adjustable work-tables carried by said bar and including gages for the side edges of a work-piece inserted bottom edge downward at the front of the platen, and gage-staffs including adjustable gage-pieces against which the top edge of the work-piece may be successively positioned for bringing the lower portion of said work-piece to different line-space positions at the printing-line, said work-tables being spaced from said bar to permit the gage-staffs to be moved to positions behind said tables, thereby disposing said gage-staffs closely adjacent the outer edges of said work-piece.

13. In a typewriting machine, the combination with a platen, of a bar extending along the platen adjacent the top thereof, means for detachably securing said bar to the machine, a pair of separately-adjustable work-tables including guides for the side edges of a work-piece inserted bottom edge downward at the front of the platen, said tables being spaced from the bar, resilient clips secured in position on said tables and including means for holding the work-piece against movement during typing, and gage-staffs slidably mounted upon said bar, said gage-staffs including gage-stops for the upper edge of the work-piece, whereby to control the line-space position of the lower portion of said work-piece, said gage-staffs being movable to position behind said tables due to the space provided between said tables and the bar.

14. In a typewriting machine, the combination with a platen, of a pair of work-tables including side gages for guiding to the printing-line a work-piece inserted bottom edge downward at the front of the platen, said work-tables including side extensions, each of said extensions having a perforation therein, the material of said extensions being drawn out around said perforations, resilient clips overlying each of said tables and having enlarged perforations fitting over the drawn-out portions of the extensions, headed screws threaded into said perforations, and a washer interposed between the head of each of said screws and the resilient clip associated therewith, whereby said screws press against said resilient clips and thereby secure the latter to the tables.

15. In a typewriting machine, the combination with a platen, and a platen-frame therefor, of an inverted L-shaped bar extending across the platen and detachably mounted on the platen-frame, a pair of work-tables, one for each side of a work-piece, said work-tables including side gages for the work-piece, said tables also including side extensions having portions thereof bent over and around said L-shaped bar, whereby to slidably secure the tables to said bar, fastening means passing through said extensions and engaging the bar, whereby to hold the tables in adjusted position thereon, downwardly-extending tongues carried by said tables for supporting the work-piece, and resilient clips fixed to said tables, the clips being spaced from said tables sufficiently to permit passage of the work-piece, said tables and clips having interlocking depressions for indenting the work-piece, to hold the same against displacement during typing.
16. In a typewriting machine, the combination with a platen and a platen-frame, of means for guiding and holding to the printing line a work-piece inserted bottom edge downward at the front of the platen, said means including a cross-bar supported on the platen-frame longitudinally of the platen, a pair of co-operating tables slidably adjustable toward and from each other substantially throughout the length of the platen, and means on said tables for holding a work-piece in position thereon, said tables being open at the top to permit insertion of the work-piece bottom edge first across the face of the tables.
17. In a typewriting machine, the combination with a platen and a platen-frame, of means for guiding and holding to the printing line a work-piece inserted bottom edge downward at the front of the platen, said means including a cross-bar supported on the platen-frame longitudinally of the platen, a pair of co-operating tables slidably adjustable toward and from each other substantially throughout the length of the platen, one or more gage-staffs slidably mounted on said cross-bar, gages on said gage-staffs including one or more stops against which the top edge of the work-piece is positioned to present the proper space on said work-piece at the printing line, and means on said tables for holding a work-piece in position thereon, said tables being open at the top to permit insertion of the work-piece bottom edge first across the face of the tables.
18. In a typewriting machine, the combination with a platen and a platen-frame, of means for guiding and holding to the printing line a work-piece inserted bottom edge downward at the front of the platen, said means including a cross-bar supported on the platen, a pair of co-operating tables slidably adjustable toward and from each other substantially throughout the length of the platen, one or more gage-staffs slidably mounted on said cross-bar, gages on said gage-staffs including one or more stops against which the top edge of the work-piece is positioned to present the proper space on said work-piece at the printing line, and means on said tables for holding a work-piece in position thereon, said tables being open at the top to permit insertion of the work-piece bottom edge first across the face of the tables, and being offset from said bar to permit movement of said gage-staffs behind the same.
19. In a typewriting machine, the combination with a platen and a platen-frame, of means for guiding and holding to the printing line a work-piece inserted bottom edge downward at the front of the platen, said means including a cross-bar supported on the platen-frame longitudinally of the platen, a pair of co-operating tables slidably adjustable toward and from each other substantially throughout the length of the platen, spring-plates overlying and spaced from said tables and forming a chute therewith, and depressions on said plates co-operating with similar depressions in said tables for frictionally holding a work-piece in said chute, said chute being open at the top to permit insertion of the work-piece bottom edge first into the chute.

ALFRED G. F. KUROWSKI.
